UNITED STATES PATENT OFFICE.

ALFRED W. ROPER, OF GLASGOW, MISSOURI.

IMPROVEMENT IN GRAIN-DRIERS.

Specification forming part of Letters Patent No. 131,464, dated September 17, 1872.

To all whom it may concern:

Be it known that I, ALFRED W. ROPER, of Glasgow, in the county of Howard and State of Missouri, have invented a certain Apparatus for Drying Grain, Meal, Malt, &c., of which the following is a specification:

My invention relates to an improvement in that form of drier in which the grain is carried successively over a series of heated metallic plates arranged vertically, and furnished with double bottoms and connecting-pipes for the introduction of steam or hot air, the grain being kept in motion and transferred gradually from the upper to the lower plates of the series by means of rotary rakes revolving on a central vertical shaft, and arranged in such manner that the grain falls alternately from the periphery and from the center of the successive plates. The general features of this form of drier are old and well-known.

My improvement consists, first, in such an arrangement of the steam-pipes, in connection with cocks and a safety-valve, that all the pans may be heated simultaneously to the same degree of temperature; or, if desired, one or more of them may be heated separately, or raised to a higher temperature than the others; I also provide waste-pipes and cocks for each separate steam-chamber. Second, in an arrangement of the rotary rakes, by which they are permitted to rise and fall freely, thereby avoiding too much resistance from local accumulations of the grain.

The general description of the machine is as follows:

The drawing is a perspective view of my improvement, a portion of the frame being broken away to reveal the parts inside.

A is the frame, which may be made of wood or metal, and of any suitable form to support the pans. B shows a bridge-beam, into which the shaft C may be stepped. D are steam-pans having an upwardly-extending rim, d, and a double bottom forming a steam-chamber, d'. E are steam-pans or tables having a steam bottom or chamber, e, similar to d'. F are steam, air, or water-pipes, as the case may be, but shown as intended for steam. The pipes F may lead directly to all the steam-chambers. G are safety-valves that may be located in one or more places. H are pipes communicating from chamber to chamber. I

are cocks for discharge of condensed steam. J is an annular pan to receive the grain, malt, &c., dropping over the edge of the lowest steam pan or table E. j is the discharge-spout of the pan J. The shaft C passes centrally through all the steam-pans and through the bars of the rakes K, which are caused to turn with the shaft by connection L with the leading arms M extending from the shaft. These arms are shown as attached to the shaft by collars N secured by set-screws n. The rake-bars are loose upon the shaft C, so as to enable them to rise or fall, according to the depth of grain in the pans. These rakes have inclined teeth k, which, in case of the pans D, carry the grain inward and discharge it through the central opening d'; but in these rakes K, above the pans or tables E, the rake-teeth are so inclined as to carry the grain outward and discharge it over the edge into the pan D beneath. e is a pulley, by which the shaft C is driven. This pulley may be at the upper or lower end of the shaft, or the shaft may be driven by cog-gearing, or in any other manner.

Either steam, heated air, or water may be passed through the chambers d e to heat the metal over which the grain, &c., is passed. In case water were used, the pipes F might be suitably modified.

The grain, &c., is fed into the upper pan at its edge, and is carried by the rake K to the orifice d' at the center, through which it drops upon the table or pan E, and being carried outward by the rake is discharged over the edge into the pan D beneath, and so on until it reaches the annular pan J, from whence it is discharged by the rake K k through the spout j.

I claim as new and of my invention—

1. The steam-heated pans D D, provided with waste-cocks I I, disks E E, and rakes K k, in combination with the pipes H, and independent connecting-pipes F F having safety-valves G G, all constructed, arranged, and operated as set forth.

2. The rakes K k, constructed as described, and loosely hung upon the shaft C, as and for the purpose set forth.

ALFRED W. ROPER.
